(57) **CLAIM**

The ornamental design for an infusion set adhesive patch, as shown and described.

DESCRIPTION

FIG. 1 is a perspective view of an infusion set adhesive patch, showing our new design;

FIG. 2 is an exploded perspective view thereof;

FIG. 3 is a top plan view thereof;

FIG. 4 is a bottom plan view thereof; and,

FIG. 5 is a side elevation view thereof.

The broken line showing is for illustrative purposes only and forms no part of the claimed design.
